UNITED STATES PATENT OFFICE.

FRANCIS TANNER, OF DETROIT, MICHIGAN, ASSIGNOR OF ONE-HALF TO
JAMES ALLEN AND MICHAEL McNAMARA, OF SAME PLACE.

ELECTRICAL ANNUNCIATOR.

SPECIFICATION forming part of Letters Patent No. 267,807, dated November 21, 1882.

Application filed August 10, 1882. (No model.)

To all whom it may concern:

Be it known that I, FRANCIS TANNER, of Detroit, in the county of Wayne and State of Michigan, have invented new and useful Improvements in Electric Annunciators; and I hereby declare that the following is a full, clear, and exact description thereof, reference being had to the accompanying drawings, which form a part of this specification.

10 The nature of this invention relates to certain new and useful improvements in the construction and operation of annunciators, such as are ordinarily employed in hotels, which are actuated by battery or electric currents.

15 The invention consists, first, in so constructing the device that the index is actuated by a change in the polarity of an electro-magnet which is actuated between two poles of a permanent magnet, the whole being brought into

20 operation the moment the circuit is complete by touching the contact or button in the room making the signal; and, second, in so constructing the device that the index is held in position by the attraction between the north and

25 south poles of the electro and permanent magnet; also, in the peculiar construction, combination and operation of the parts, as more fully hereinafter described.

Figure 1 is a front elevation of a section of my annunciator, showing the index pointing to the number of the room with which it is connected, and in dotted lines the position of said index when not in active use. Fig. 2 is a rear perspective, with a portion of the covering of the electro-magnet broken out.

In the accompanying drawings, which form a part of this specification, A represents the front of the annunciator, which is made up of as many sections as the number of rooms with 40 which it is desired to make connection, and for each one of these sections there is provided an index, D, secured to the trunnion B of the electro-magnet E, which projects through the front of the annunciator, and the other trunnion, B', is supported in the bracket C, which is secured to the rear face of the annunciator-front. This bracket should be made of brass or other electrical conducting material.

H is a permanent magnet of the U or horse-shoe form, and this is centrally secured to the

rear side of the annunciator-front, and the metal trunnion, which supports the index, passes through the center of this permanent magnet and is not insulated therefrom, but so arranged that they are at all times in electrical contact. 55

E is a wooden case, inclosing an electro-magnet with a soft-iron core, and constructed in the usual way. The trunnion upon which the index is supported forms a connection with one end of the wire of the electric magnet, 60 while the corresponding trunnion passes through the bracket and forms the bearing and connection at that end of the device. To prevent the pole of the electro-magnet from 65 coming directly in apposition to the opposite pole of the permanent magnet a stop, a, is secured to the case of the electro-magnet, designed in the change of polarity of the same to impinge against the side of the bracket 70 when in either position.

F is the wire connecting with the battery and one end of the bracket C.

G is the return-wire, making connection with the permanent magnet, through which connection is made with the electro-magnet. After the index has been used to indicate a call it is held in position until returned to its original position, as shown in dotted lines in Fig. 1, by any suitable mechanism such as is ordinarily employed for that purpose. 80

In practice, when the circuit is completed by touching the button in the room from which the call is made the current passes through the wire F to the bracket with which it is in 85 electrical connection, and it passes through the bracket, through the wire which is connected with the electro-magnet, through the latter to the return-wire G, and by this means and arrangement of parts an instant change 90 is effected in the polarity of the electro-magnet, which reverses its original position, carrying the index with it, this index being so arranged with relation to the axis of the said magnet as to point to the number of the room 95 making the call.

What I claim as my invention is—

1. The combination of an electric magnet having centrally-located trunnions and a suitable indicator attached to an extended portion 100

of one of said trunnions, and centrally pivoted between the extremities of a fixed permanent magnet and a curved bracket inclosing said fixed and pivoted magnets, and secured to a suitable frame or base, and a suitable pin or stop adapted to rest against said bracket and prevent direct opposition of the poles of the magnets, and suitable wires whereby the pivoted magnet is oscillated between the poles of the permanent magnet by the alternate reversal of the current passing therethrough, and the attraction and repulsion of the permanent magnet, substantially as set forth.

15 2. The combination of the curved fixed

bracket C and fixed permanent magnet H, and a suitable frame or base with an electro-magnet provided with trunnions pivoted respectively in the bracket and fixed magnet, the stop a, and a suitable indicator, D, secured to the trunnions of the electro-magnet, and operated by the alternate reversal of a single current in the electro-magnet and the normal attraction of the permanent magnet, substantially as shown and described.

FRANCIS TANNER.
